UNITED STATES PATENT OFFICE.

JACOB HUMMEL, OF ELKHART, INDIANA.

DESIGN FOR A VEHICLE-STEP PAD.

SPECIFICATION forming part of Design No. 24,742, dated October 8, 1895.

Application filed September 4, 1895. Serial No. 561,468. Term of patent 7 years.

To all whom it may concern:

Be it known that I, JACOB HUMMEL, a citizen of the United States, residing at Elkhart, in the county of Elkhart and State of Indiana, 5 have invented and produced a new and original Design for a Vehicle-Step Pad, of which the following is a specification, reference being had to the accompanying drawings, forming part thereof.

10 Figure 1 is a plan view of a step-pad embodying my new design, and Fig. 2 is an edge view thereof.

Similar characters of reference indicate corresponding parts in both views.

The leading feature of my design consists 15 in the step-pad having elongated arms projecting from two adjacent sides, the opposite sides having devices of hook-like conformation, the same projecting outward slightly from the edges of the step and then returning beneath the same.

I claim—

The design for a vehicle step pad herein shown and described.

JACOB HUMMEL.
